UNITED STATES PATENT OFFICE.

JOHN B. PITTS, OF WINNETKA, ILLINOIS.

RADIODETECTOR.

Application filed January 31, 1925. Serial No. 5,983.

To all whom it may concern:

Be it known that I, JOHN B. PITTS, a citizen of the United States of America, residing at Winnetka, in the county of Cook and State of Illinois, have invented certain new and useful Improvements in Radiodetectors, of which the following is a specification.

This invention relates to the solid element type of detectors or adapters employed in radio-telephony apparatus, and has for its various objects:—

To provide a structural formation and combination of parts in a shell shaped holder for the complementary electrical elements of the detector, by means of which said elements are substantially supported in an adjustable manner in proper operative relation to each other, and are enclosed and protected from dust and other injurious local influence. The holder is adapted for ready and convenient attachment to the front, rear or base of the enclosing cabinet of the apparatus.

To provide a structural formation of parts, whereby an electrical element of a crystal or like solid detector element is held in a fixed and effective condition in the holder, with an avoidance of a solder or like metallic embedment for holding a crystal or like element in conductive position, and the consequent decrease in the sensitivity of the element, all as will hereinafter more fully appear. In the accompanying drawing:

Fig. 1, is a side elevation.

Fig. 2, is a central longitudinal section, showing the invention as applied to the cat's whisker type of crystal detectors.

Fig. 3, is a perspective view of the detector parts shown in Fig. 2, in separated condition.

Fig. 4, is a similar perspective view of the parts if the adjustable unit of a crystal detector is of the type in which one crystal has conductive contact with another crystal.

Fig. 5, is a longitudinal section of the detector of the type referred to in connection with Fig. 4.

Like reference numerals indicate like parts in the several views.

The main casing 1 of the detector is preferably formed of a section of metallic tubing, threaded internally along its length for screw-threaded engagement with other associated parts of the device.

The shell or container for the stationary crystal or like solid electrical element of the

detector, is formed of a suitable non-electric material, and consists of an externally and internally screw threaded tubular member 2, provided at one end with an out turned stop collar or flange 3, and at the other end with an orificed head formed by an inturned flange 4 as shown. The central orifice so formed affords a bearing or abutment for a crystal element 5 which is exposed through said orifice for electrical contact with the complementary crystal or other usual element of the detector.

In the construction shown, the external screw threads of the shell or container 2 have positioning engagement with the screw threads in an end of the main casing 1, with the stop collar 3 providing a stop or abutment for the parts, as well as a part of the attaching means for a terminal ring member 6, a side extension of which carries a screw terminal 7 for connection of a line wire of the apparatus.

Associated with the shell or container 2 is an externally screw threaded follower head 8 of metal, adapted to screw into the internally screw threaded bore of the shell or container 2 to firmly clamp and position the crystal element 5 in place in the cavity of said shell as shown. At one end the head 8 is provided with a fixed operating stem 9 for convenient rotation in an adjustment of parts, and in the preferred construction shown the stem 9 is screw threaded along its length for the reception of binding nuts 10, by which attachment is made to supporting plate bracket 11, preferably of the Z form shown, and by means of which the detector is supported in the enclosing casing of a radio apparatus. In the construction shown the bracket plate 11 is interposed between the flanged end 3 of the shell 2 and the aforesaid nuts 10, with said nuts also acting to hold between them a conducting line wire of the circuit of the apparatus.

The other and complementary electrical element 12 of the detector has, as usual, an adjustable relation to the aforesaid fixed crystal or like element 5, and may be of the well known "cat's whisker" type, comprising a spiral or serpentine section 13 of wire, the free end of which is adapted for electrical contact with the crystal element 5, while its other end has fixed attachment to a stud 14 on one end of an externally screw threaded head 14 having adjustable engagement with the internal screw threads of the

main casing 1. The attachment being preferably attained by a bent end 13' of the wire spiral 13 fitting a diametric slit in the aforesaid stud 14'. In this specific arrangement 5 of parts as shown in Figs. 2 and 3, the head 14 is of a solid form and is provided with a central fixed stem 15 having an operating handle 16 for convenient rotation of the head in effecting an initial adjustment or replacement of parts.

In Figs. 4 and 5, a modified arrangement is shown in which a crystal element 17 constitutes the adjustable electrical contact element of the detector, with a modified formation of the adjustable follower head for said crystal as follows:

The head 18 above referred to, is externally screw threaded, as in the case of the shell or container 2 heretofore described, 20 and is formed with a screw threaded bore at one end of which is an orificed head formed by an inturned annular flange 19, similar to said shell or container 2, with the central orifice so formed providing a bearing or abutment for the crystal element 17, which projects through said orifice for electrical contact with the stationary crystal element 5 aforesaid. In this modified construction an externally screw threaded plug 20 has adjustable engagement with the screw threaded bore of the head 18 to firmly clamp 30 and hold the crystal element 17 in proper position.

At one end the plug 20 carries a stem 21 having an operating handle or knob 22 at its outer end for the convenient rotation of said plug and the head 18 in effecting a replacement or an adjustment of parts.

Having thus fully described my invention 40 what I claim and desire to secure by Letters Patent, is:—

1. In a radio detector, the combination of a main casing of conducting material formed with a screw threaded bore along 45 its length, a container of non-conducting material screw threaded externally for engagement in one end of the main casing and formed with a screw threaded cavity for the reception of a crystal contact member and with a centrally orificed end wall providing a bearing for said crystal member,

an externally screw threaded follower head of conducting material having engagement in the bore of the container to hold said crystal member in position, an externally 55 screw threaded plug of conducting material carrying an electrical contact member in operative relation to the crystal member and formed with a screw threaded periphery in adjustable engagement with the bore of the 60 main casing, a terminal member connected to the main casing, and a companion terminal member connected to the aforesaid follower head of the container.

2. In a radio detector, the combination of 65 a main casing of conducting material formed with a screw threaded bore along its length, a container of non-conducting material screw threaded externally for engagement in one end of the main casing and formed 70 with a screw threaded cavity for the reception of a crystal contact member and with a centrally orificed end wall providing a bearing for said crystal member and with an end turned flange at its other end, an 75 externally screw threaded follower head of conducting material having engagement in the bore of the container to hold said crystal member in position, an externally screw threaded plug of conducting material carrying 80 an electrical contact member in operative relation to the crystal member, and formed with a screw threaded periphery in adjustable engagement with the bore of the main casing and with a central screw 85 threaded stem extending beyond the main casing, an externally screw threaded plug of conducting material carrying an electrical contact member in operative relation to the crystal member and formed with a screw threaded periphery in adjustable engagement with the bore of the main casing, 90

an externally screw threaded plug of conducting material carrying an electrical contact member in operative relation to the crystal member and formed with a screw threaded periphery in adjustable engagement with the bore of the main casing, a terminal member of the ring form arranged between an end of the main casing and the end flange of the aforesaid container, and a companion terminal member connected to the central stem of the follower head aforesaid.

Signed at Chicago, Illinois, this 28th day of January, 1925.

JOHN B. PITTS.
